MERCHANDISE DISPLAY RACK

Douglas G. Covell, Upper Arlington, and Charles A. Wells, Marysville, Ohio, and Michael C. Wilson, Glen Ellyn, Ill., and Raymond A. Krusinski, Gahanna, Ohio, assignors to Pretty Products, Inc., Coshocton, Ohio

Filed Mar. 17, 1975, Ser. No. 558,637

Term of patent 14 years

Int. Cl. D6—04; D20—02
U.S. Cl. D6—85

FIG. 1

FIG. 2

FIG. 3

FIG. 6

FIG. 5

FIG. 4

FIG. 7

FIG. 9

FIG. 8

FIG. 10

FIG. 1 is a perspective view of a merchandise display rack embodying this design.

FIG. 2 is a fragmentary view thereof and comprises a top plan view of the base on an enlarged scale.

FIG. 3 is a fragmentary elevational view thereof as seen from the bottom side of FIG. 2.

FIG. 4 is a fragmentary elevational view thereof as seen from the right side of FIG. 2.

FIG. 5 is a fragmentary vertical sectional view on an enlarged scale taken along line 5—5 of FIG. 2.

FIG. 6 is a vertical sectional view on an enlarged scale taken along line 6—6 of FIG. 2.

FIG. 7 is a vertical sectional view on an enlarged scale taken along line 7—7 of FIG. 2.

FIG. 8 is a vertical sectional view on an enlarged scale taken along line 8—8 of FIG. 2.

FIG. 9 is a vertical sectional view on an enlarged scale taken along line 9—9 of FIG. 2.

FIG. 10 is a bottom plan view on an enlarged scale of the merchandise display rack as seen in FIG. 1 but with the upstanding support rods omitted.

Merchandise packages are shown in broken lines suspended on the merchandise display rack in FIG. 1 for illustrating the use thereof and do not form a part of this design.

We claim:

The ornamental design for a merchandise display rack, substantially as shown and described.
